UNITED STATES PATENT OFFICE.

CHARLES H. ODERS, OF REDDING, CALIFORNIA, ASSIGNOR TO SOPHY D. ODERS, OF REDDING, CALIFORNIA.

RIFFLE AND AMALGAMATOR-BOX.

1,097,352.

Specification of Letters Patent. Patented May 19, 1914.

Application filed February 3, 1913. Serial No. 745,806.

To all whom it may concern:

Be it known that I, CHARLES H. ODERS, a citizen of the United States, residing at Redding, in the county of Shasta and State 5 of California, have invented new and useful Improvements in Riffles and Amalgamator-Boxes, of which the following is a specification.

This invention relates to an amalgamator 10 of the sluice box type.

The object of the invention is to provide a simple, practical and compact amalgamator which is constructed with the main object in view of providing the largest amalgamating surface possible.

Another object of the invention is to provide means for trapping any floured amalgam or quicksilver which might be removed from the plates by the scouring action of 20 material passing over the plates.

A further object of the invention is to provide means for keeping the sands or lighter materials in suspension in the wash water so as to prevent choking or banking behind the 25 riffles in the box.

The invention consists of the parts and the construction and combination of parts as hereinafter more fully described and claimed, having reference to the accompanying 30 drawings, in which—

Figure 1 is a longitudinal section on line X—X, Fig. 2. Fig. 2 is a plan view of the apparatus.

Referring to the drawings, A indicates a 35 rectangular-shaped amalgamator box, which may be constructed of any suitable material but preferably of heavy sheet iron. The bottom of the box is covered with a removable amalgamating plate 2 and is also provided with a series of vertically positioned, removable amalgamating plates 3. The sides of the box may be grooved, or, as here shown, provided with cleats 4 for the purpose of holding the plate in position.

45 Positioned intermediate of the plates 3 and spaced a suitable distance above the bottom plate 2 is a second series of removable amalgamating plates 5 which are secured between the sides of the box by cleats, as 50 at 6.

7 indicates a series of perforated spray pipes supported crosswise of the box between the plates 3 and 5 which are connected at their outer ends with a manifold or 55 distributor pipe 8. This is in turn connect-

ed by a flexible hose or like means with a centrifugal pump or source of water supply having sufficient pressure to operate the spray pipes 7.

By referring in particular to Fig. 1 of the drawings, it will be seen that the amalgamating box A is supported in a suitable framework B and is inclined in the manner of a sluice box to produce a natural flow through the box. The pulp or sands discharged from the stamp mill which contain the amalgamable precious metals in a finely divided state is delivered, together with a sufficient quantity of wash water, at the upper end of the box, as indicated at 9, 60 through a funnel-shaped entrance or like device and is directed down toward the bottom plate where it is deflected and forced in an upward direction by the plate 3. It then passes over the top edge of the plate 3 and 65 is again deflected downwardly toward the bottom plate by the plate 5 when the current flow forces the pulp under the plate 5 against the second plate 3 where it is again deflected upwardly between the plates 3 and 70 5. It will then be seen that the pulp on passing through the box is constantly impinged or brought into contact with the several amalgamating surfaces disposed in the box, thus giving ample opportunity to 75 adhere to one of the amalgamating surfaces in the box.

The vertical amalgamating plates disposed in the bottom of the box not only serve the function of plates but also act as 80 riffles in the box behind which such values, as floured quicksilver and sulfites, may be trapped; the force of the downwardly projected stream of water from the spray pipes being sufficient to remove the lighter pulp or 85 sands which will finally be discharged in the lower discharge end of the box, as at 11.

The upper end of the distributor pipe may be provided with a suitable valve for the purpose of controlling the force of the 90 downwardly directed stream discharging from the spray pipes, thus making it possible to adjust the force of the agitating water to a point where it will only remove the lighter sands and prevent banking of 95 the same.

The construction of the amalgamator box and the mounting of the plates make it possible to quickly remove or insert the different plates when it is desired to clean 100 110

them, without losing much time or requiring the employment of skilled mechanics.

The amalgamating box is simple and compact in construction and efficient in its action and takes less space than similar apparatus. The materials and finish of the several parts of the amalgamator are such as experience and judgment of the manufacturer may dictate.

10 Having thus described my invention, what I claim and desire to secure by Letters Patent is—

In an amalgamating apparatus, an inclined sluice with a rising floor at the discharge end, means to supply pulp and water at the upper end thereof, a removable amalgamating bottom plate, a series of removable transverse plates at right angles with said bottom plate and having their

lower edges spaced above said bottom, a 20 second series of removable plates arranged in alternation in the first mentioned plates and having their lower edges in contact with said bottom plate, said last mentioned plates having their upper edges curved to form a 25 flow surface for the impregnated solution, and spray pipes between said plates constructed to discharge spray downward in opposition to the normal flow of the impregnated solution as it passes through the 30 sluice box.

In testimony whereof I have hereunto set my hand in the presence of two subscribing witnesses.

CHARLES H. ODERS.
